US0D1018203S

(12) **United States Design Patent** (10) Patent No.: **US D1,018,203 S**
(45) Date of Patent: ** Mar. 19, 2024

(54) **SIPPY CUP**

(71) Applicant: **Elgin Chan**, Guangzhou (CN)

(72) Inventor: **Elgin Chan**, Guangzhou (CN)

(**) Term: **15 Years**

(21) Appl. No.: **29/814,143**

(22) Filed: **Nov. 3, 2021**

(51) LOC (14) Cl. **07-01**

(52) U.S. Cl.

USPC **D7/510**; D7/392.1

(58) **Field of Classification Search**
